GATE VALVE BODY

Marvin H. Grove, 340 Hillside Ave., Piedmont, Calif.

Filed July 21, 1964, Ser. No. 80,947

Term of patent 14 years

(Cl. D91—3)

FIGURE 1 is a perspective view of a gate valve body showing my design;

FIGURE 2 is a fragmentary detail showing an upper corner portion of the valve body looking toward one side thereof;

FIGURE 3 is a fragmentary detail looking toward one end of the body and showing the construction of one side of the body.

The side of the body opposite to that shown in FIGURE 1, and the rear are identical to the front and sides shown.

This application is a continuation-in-part of my application Serial No. D-76,360, filed Aug. 26, 1963, and now abandoned.

I claim:

The ornamental design for a gate valve body, substantially as shown and described.
